WEAR TAKE-UP ADJUSTING MEANS FOR RECIPROCATING KNIVES OF CLOTH-CUTTING MACHINES

William Aaron, Brooklyn, N. Y.

Application July 17, 1946, Serial No. 684,191

3 Claims. (Cl. 30—273)

1

This invention relates to cloth-cutting machines which are equipped with reciprocating knives; and the invention has reference, more particularly, to a novel construction of knife or cutting blade for such machines.

The invention has for an object to provide a construction of knife or cutting blade for cloth-cutting machines which is provided with novel coupling means adapted to permit its adjustment relative to its driving means in such manner as to change its operative position in the machine, whereby to compensate for recession of its cutting edge due to grinding down thereof by the knife sharpening means with which cloth cutting machines of modern design are usually provided.

Other objects of this invention, not at this time more particularly enumerated, will be understood from the following detailed description of the same.

Illustrative embodiments of this invention are shown in the accompanying drawings, in which:

Fig. 1 is a fragmentary side elevational view of a cloth-cutting machine of the reciprocating knife or cutting blade type, as equipped with the novel blade structure according to this invention; and Fig. 2 is a fragmentary front elevational view of the same, with parts in section.

Fig. 3 is an enlarged fragmentary view showing the novel coupling means of the blade as initially engaged with the blade driving means, the machine standard and blade guide being shown in section; and Fig. 4 is a view similar to that of Fig. 3, but showing the novel coupling means of the blade as adjusted relative to the blade driving means, whereby to advance the position of the blade cutting edge in compensation for cutting edge wear.

Fig. 5 is a fragmentary face view of a modified form of cutting blade provided with the novel coupling means of this invention; and Fig. 6 is a fragmentary face view of a cutting blade provided with a modified form of the coupling means.

Similar characters of reference are employed in the above described views, to indicate corresponding parts.

Referring to the drawings, the reference character 10 indicates the base of a cloth-cutting machine, from which rises the standard 11 in connection with the upper end of which is supported the head 12 by which the motor and blade driving mechanism of the machine is carried. The standard 11 is provided with the usual forwardly open slot or guideway 13, in which the cutting blade, when it is operatively mounted in the machine, is reciprocated. The means for re-

15 reciprocating the cutting blade comprises a vertically reciprocable slide block 14 which runs in the slideway 15 with which the head 12 is provided. Said slide block 14 is reciprocated by a motor driven crank-wheel 16, or like suitable means, to which it is operatively connected by a connecting rod 17. Means is provided at the lower end of said slide block 14 for detachably coupling thereto the cutting blade 18; said means comprising a dependent arm 19 which terminates in a coupler jaw 20, from one face of which projects an externally screw-threaded coupler stud 21 which is unitary therewith. Threaded onto said coupler stud 21 is a clamp nut 22 which is provided with a base flange 23 to oppose said coupler jaw 20. The upper end of the cutting blade 18 is ordinarily bifurcated to provide a notch for the reception of the coupler stud 21, so that said blade end portion straddles the latter, whereupon it may be clamped between the coupler jaw 20 and the clamp nut 22, when the latter is tightened home on the coupler stud 21, thus rigidly coupling the blade to the driving means by which it is vertically reciprocated in the slot or guideway 13 of the standard, and in such relation to the latter that its cutting edge 24 projects freely and forwardly from the same.

20 In modern cloth-cutting machines of the reciprocating cutting blade type, means (not shown but familiar to the art) is provided which may be brought into service from time to time, as necessity requires, whereby to resharpen the exposed cutting edge 24 of the blade 18. Repeated use of such sharpening means gradually wears down the cutting blade, so that its cutting edge recedes toward the standard 11, and eventually in such close proximity thereto that use of the blade can no longer be efficiently availed of, and consequently the blade must be discarded and replaced by a new blade, notwithstanding there is still a substantial amount of available blade which would otherwise be practically usable. It is to avoid this waste, and to permit extended use of a blade beyond the period when it would 25 have to be discarded, which is the object of this invention to attain. To attain this objective, I have constructed the upper end of the blade in such manner as to permit its forward advancing adjustment relative to the means by which it is operatively coupled to the reciprocating or driving mechanism therefor, whereby an additional amount of the blade material is made available for service, and subject to further sharpening thereof. To this end, the upper end portion of the blade 18 is provided with a bifurcated forma-

tion affording a downwardly extending entering notch 25 intermediate the arms 26 thereof. Said notch 25 communicates at its lower or inner end with a coupler stud receiving opening or transverse seating slot 27 of a height conforming to the vertical diameter of the coupler stud 21, and of a width substantially exceeding the transverse-diameter or width of said coupler stud 21. Said opening or seating slot 27 is bounded on its outer or forward side by a perpendicular margin or shoulder 28 and on its inner or rearward side by a similar perpendicular margin or shoulder 29. Preferably, the opposite sides of said coupler stud 21 are cut away to form perpendicular flat abutment faces, comprising an outer or forward abutment face 30, and an inner or rearward abutment face 31. Springing from the inner side of at least one of the arms 26 is a laterally projecting clamp nut bearing tongue 32 which overhangs the opening or seating slot 27, with its free end spaced from the opposite arm 26, whereby to provide a coupler stud entranceway 33 leading from the notch 25 into the receiving opening or seating slot 27.

To attach the blade 18 in initial operative position in the machine, and in coupled relation to the driving mechanism therefor, the clamp nut 22 being loosened, the back edge portion of the blade is entered in the guideway 13 of the standard 11, and then the blade is pushed upward to pass the coupler stud 21 through the notch 25 and entranceway 33 and into the receiving opening or seating slot 27. When thus disposed, the blade 18 is adjusted so as to abut the outer or forward margin or shoulder 28 of the opening or slot 27 against the outer or forward abutment face 30 of the coupler stud 21, thus positioning the blade in operative perpendicular position, with its cutting edge 24 outwardly projecting from the guideway 13 of the standard 11. After the blade is thus operatively positioned, the clamp nut 22 is tightened home on the coupler stud 21, whereby to clamp the blade between the flange 23 of said clamp nut 22 and the coupler jaw 29. Owing to the provision of the bearing tongue 32, a generous and adequate bearing surface above the coupler stud 21 is provided on one face of the blade for frictional engagement by the coupler jaw 29, and on the opposite face of the blade for frictional engagement by the flange 23 of the clamp nut 22, whereby the blade is firmly gripped in an adequately balanced manner both above and below the coupler stud 21, and thus strongly and non-shiftably coupled in operative relation to the slide block 14 so as to be longitudinally reciprocated thereby. Such initial coupled relation of the blade 18 to the driving mechanism therefor is shown more particularly in Fig. 3.

During use of the thus initially mounted blade 18, as the cutting edge 24 thereof dulls, the same may be sharpened from time to time. Such sharpening, as repeated, wears down said cutting edge 24, thereby causing it to recede toward the standard 11. When, under such circumstances, the cutting edge 24 approaches the standard too closely for further efficient operation, the blade may be adjusted laterally to advance the receded cutting edge relative to the standard 11, whereby to again permit effective operation thereof and further continued use of the blade. To accomplish this, the clamp nut 22 is loosened to release engagement of the blade by the flange 23 thereof, whereupon the blade may be moved laterally outward until the inner or rearward margin or

shoulder 29 of the seating slot 27 abuts the inner or rearward abutment face 31 of the coupler stud 21, thus perpendicularly aligning the blade in such advanced position (see Fig. 4). After the blade is thus adjusted, the clamp nut 22 is again tightened home so as to bind the blade between its flange 23 and the coupler jaw 29. In this adjusted position of the blade, the tongue 32 continues to dispose its opposite surfaces respectively for engagement by the coupler jaw 29 and clamp nut flange 23, so that the blade is strongly gripped and bound both above and below the seating slot 27 in a balanced grip adapted to firmly hold the blade subject to operation in its advanced position. It will be obvious, that, as thus repositioned, not only may further use of the blade be made, but further resharpening of its cutting edge 24 may be carried out, until the latter recedes to the point where further use is impractical, and discarding of the blade finally unavoidable. The additional use, however, which the adjusted advance of the blade permits adds greatly to the length of useful life of the blade, and conserves the material thereof with resultant economy.

If desired, the adjustable blade may be provided with an additional rearward cutting edge 24' (see Fig. 5), whereby the blade may be reversed after one edge, as edge 24, has been consumed, thus further adding to the useful life of the blade.

In Fig. 6 I have shown a somewhat modified form of the coupling end portion of the blade, whereby instead of a single bearing tongue 32, I provide two bearing tongues 32' and 32" respectively springing from opposite sides of the notch 25, but separated to provide an intermediate entranceway 33' leading to the underlying seating slot 27. It will be apparent that said bearing tongues 32' and 32" provide the desired bearing surfaces above the coupler stud 21 subject to the grip of the coupler jaw 29 and clamp nut flange 23.

Having now described my invention, I claim:

1. In a cloth-cutting machine of the reciprocating knife type, in combination with the vertically reciprocated coupler jaw of the machine, a screw-threaded coupler stud projecting from said jaw, a clamp-nut threaded onto said coupler stud, a knife attachable to said coupler jaw, said coupler stud being provided at respective opposite sides with perpendicular abutment faces, said knife having a bifurcated upper end portion providing the same with a downwardly extending entering notch which terminates at its lower end in a transverse seating slot to receive the extension therethrough of said coupler stud, said seating slot being of substantially greater width than the transverse width of said stud and of a height corresponding to the vertical diameter of said stud, said seating slot having perpendicular side margins respectively subject to abutment by the respective abutment faces of said stud according to the laterally adjusted position of said knife relative to said stud, and said knife end portion having clamp nut bearing means disposed to overhang said seating slot, whereby to be lapped by said clamp nut, in common with other areas of the knife adjacent said seating slot, so as to grip and rigidly hold said knife between said nut and coupler jaw in selected laterally advanced adjusted position.

2. In a cloth-cutting machine of the reciprocating knife type, in combination with the vertically reciprocated coupler jaw of the machine, a

screw-threaded coupler stud projecting from said jaw, a clamp-nut threaded onto said coupler stud, a knife attachable to said coupler jaw, said coupler stud being provided at respective opposite sides with perpendicular abutment faces, said knife having a bifurcated upper end portion providing the same with a downwardly extending entering notch which terminates at its lower end in a transverse seating slot to receive the extension therethrough of said coupler stud, said seating slot being of substantially greater width than the transverse width of said stud and of a height corresponding to the vertical diameter of said stud, said seating slot having perpendicular side margins respectively subject to abutment by the respective abutment faces of said stud according to the laterally adjusted position of said knife relative to said stud, and said knife end portion having a clamp nut bearing tongue springing from one side of said entering notch but terminating short of the opposite side of the latter to provide an entranceway of a width adapted to pass said stud therethrough and into

5 said seating slot, said bearing tongue being disposed to overhang said seating slot, whereby to be lapped by said clamp nut, in common with other areas of the knife adjacent said seating slot, so as to grip and rigidly hold said knife between said nut and coupler jaw in selected laterally advanced adjusted position.

10 3. In a cloth cutting machine of the reciprocating knife type as defined in claim 2, wherein the knife is provided with both forward and rearward cutting edges, whereby to be both reversible and laterally adjustable relative to its coupled connection with the coupler jaw.

15 WILLIAM AARON.
